STORAGE TANK

Filed June 15, 1927

Inventor:
Warren K. Russell

by Rev. N. Goddard, Atty.

UNITED STATES PATENT OFFICE

WARREN K. RUSSELL, OF NEWTON, MASSACHUSETTS, ASSIGNOR TO JAMES RUSSELL
BOILER WORKS CO., OF BOSTON, MASSACHUSETTS, A CORPORATION OF MASSACHU-
SETTS

STORAGE TANK

Application filed June 15, 1927. Serial No. 199,102.

This invention relates to storage tanks, such as are employed in large office buildings and elsewhere for the storage of oil and other purposes where tanks of very considerable size are used that are subjected to considerable internal pressure at times, and may also be subjected to external pressure because of a partial vacuum occurring in the interior.

The sides, as well as the top, and bottom of such tanks are commonly made of steel plates riveted or otherwise jointed together by leakproof joints, and to prevent buckling of the plates a fairly heavy gage of plate is ordinarily used.

15 It is the object of the present invention to provide a construction by which great economy may be effected through the use of lighter weight plates, while at the same time avoiding the danger of buckling of the plates under external or internal pressure.

With this and other objects in view the invention consists, generally speaking, in a construction and arrangement that stiffens and reinforces the plates at intervals through

25 the use of a combined series of tie-rods and hollow braces so related that very great stiffness results so that the tank, when made of thinner than the usual gage of metal, is thoroughly braced and supported against buckling under the strains to which it may be subjected by pressure.

Generally speaking the invention comprises a tank whose opposite side walls are provided with opposite aligned perforations combined 35 with a series of hollow braces whose opposite ends abut against, and are firmly secured to, the portions of the side walls immediately surrounding each pair of perforations, while a series of tie rods, arranged within the perforations, have their projecting ends provided with thrust-sustaining heads or members engaging the exterior surrounding portions of the wall to prevent outward bulging of the plates.

45 This and other features of the invention will be described in the following specification and will be defined in the claims hereto annexed.

In the accompanying drawings I have illustrated a simple and convenient form of

construction and arrangement embodying the principles of this invention, in which:

Figure 1 is a vertical section through a storage tank of the class described, the side walls being partly broken away through the middle portion to permit the showing on a large scale. 55

Figure 2 is a vertical central section through one of the hollow braces showing the construction by which the side walls are 60 braced against internal and external pressure.

In the practice of this invention, according to the form illustrated in the drawings, a tank, in this case of general rectangular form, is built with side walls 1, top 2 and bottom 3, comprising plates of sheet steel or the like tightly joined together at their overlapped edges to provide leakproof joints. The specific manner in which these plates are 70 joined together is not material, and in the drawings I have shown such joints made tight by the use of short tightening bolts or rivets.

On opposite sides of the tank are arranged 75 a series of pairs of perforations of a size to allow the passage of a suitable tie-rod, the opposite perforations of each pair being aligned to receive a single tie-rod.

A tubular brace, of a length to reach across 80 from one side wall to the opposite one, is interposed so that its opposite ends abut against the adjacent side wall around a pair of aligned perforations therein. A tie-rod 8 is passed through the two side wall perforations surrounded by the tubular brace, as well as through the tube, such tie-rod being of sufficient length to leave projecting ends extending beyond the exterior faces of the side walls. 85

If desired, spacing washers, as shown at 90 5, may be inserted in the ends of the hollow braces to secure accurate spacing between the relatively small tie-rod and the surrounding hollow brace, while at the same time 95 serving to position both ends of the brace preparatory to welding or otherwise securing the ends of the brace to the inner faces of the side walls.

Preferably a stiffening disk 7, centrally 100

perforated for the tie-rod, and having somewhat larger diameter than the diameter of the hollow brace, is placed over the projecting end of the tie-rod, and a thrust-supporting head on each end of the tie-rod, as shown at 9, in the form of a nut or head, is employed to prevent outward bulging of the opposite plates.

One of the heads may be integral with the tie-rod and the other in the form of a nut having threaded engagement for drawing the plates firmly against the interior abutting ends of the hollow brace.

To prevent leakage, the seam formed by the ends of the brace in contact with the side walls, may be electrically welded, as indicated at 6, the joints between the stiffening plate 7, and the outer face of the side wall, as well as the joint between the head and the stiffening plate, and the head and tie-rod may also be welded together to form a leak-proof joint. By thus securing all the parts together a very firm and rigid structure is provided that is capable of withstanding heavy pressure from the inside or from the outside without loosening the seams or permitting the plates to buckle in either direction.

Obviously, with this system of reinforcement, materially thinner plates may be used than if only ordinary tie-rods should be used since the whole structure is rendered very rigid.

What I claim is:

1. A pressure-tight storage tank whose opposite sides are provided with aligned perforations, tubular braces of substantially larger internal diameter than said perforations interposed between the sides with their opposite ends welded to said sides around a pair of aligned perforations, tie-rods inserted through said tubular braces with their opposite ends projecting through said perforations, thrust-supporting heads secured to the outer ends of said tie-rods, perforated centralizing washers surrounding said tie-rods and engaging the inside walls of the braces.

2. A pressure-tight storage tank whose opposite sides are provided with aligned perforations, interior hollow braces interposed between said side walls with their ends abutting against and welded to said side walls around said perforations, exterior stiffening plates also welded to said side walls and having perforations aligned with the perforations in the side walls, and tie-rods inserted through said perforations and through the hollow braces, said tie-rods having exterior heads on their outer ends engaging said stiffening plates and serving to clamp said stiffening plates and said braces together against opposite faces of the side walls, substantially as described.

3. A pressure tight storage tank whose op-

posite sides are provided with aligning perforations, tubular interior braces of substantially larger internal diameter than said perforations, a tie rod projecting through the aligned perforations concentrically with the tubular brace, a spacing washer having internal engagement with the tie rod and peripheral engagement with the interior of the tubular brace, an external reinforcing plate surrounding the ends of the tie rods that project outside of the tank for supporting the heads of the tie rod, said tubular brace, said reinforcing plate and said tie rod head being welded around their peripheries to unite them integrally with the adjacent wall of the tank.

In witness whereof, I have subscribed the above specification.

WARREN K. RUSSELL.
